CORSELET

Filed Feb. 26, 1930

L. M. Wessell, INVENTOR
BY Victor J. Evans
ATTORNEY

UNITED STATES PATENT OFFICE

LANA MAUD WESSELL, OF PALATINE BRIDGE, NEW YORK

CORSELET

Application filed February 26, 1930. Serial No. 431,481.

This invention relates to improvements in corsets and more particularly to what are known as corselets, and I have found that while a corselet is designed to produce a straight line figure, such of these articles as have been put on the market present the disadvantage that they do not sufficiently confine the body above the waist line and there is therefore the tendency for the stomach to increase in size, thus not only causing discomfort but also detracting from the value of the article as a shape or contour modifying means. The present invention has as its primary object to provide a corselet which will embody means for suitably confining the body above the waist line at the front thereof so as to overcome the disadvantages presented by the ordinary forms of corselets, as above outlined, and the invention contemplates, in this connection, such a construction of the garment that it will comfortably conform to the body of the wearer and maintain the body in graceful form and prevent any fullness of the stomach.

Another object of the invention is to provide a corselet embodying portion which will provide for the passage of air so as to ventilate the garment to such an extent as to render it more comfortable to wear than the ordinary garment of this type.

This invention also consists in certain other features of construction and in the combination and arrangement of the several parts, to be hereinafter fully described, illustrated in the accompanying drawing and specifically pointed out in the appended claims, it being understood that minor changes may be made so long as they fall within the scope of the claims.

In describing my invention in detail, reference will be had to the accompanying drawing, wherein like characters denote like or corresponding parts throughout the several views, and in which:—

Figure 1 is a perspective view looking at the front of the corselet.

Figure 2 is a rear view thereof.

Figure 3 is a detail vertical sectional view taken substantially on the line 3—3 of Figure 1.

The corselet embodying the invention is, so far as regards its general shape and dimensions, substantially like the ordinary garment of this type, and the garment includes a front section 1, side sections 2, and a back section 3 and these sections are connected at their meeting margins by the usual seams 4.

In accordance with the principles of the invention, an oblong rectangular insert 5 of lace or woven net material is inserted between the margins of adjacent sections of the front 1, which sections are indicated by the numerals 6 and 7, and this insert extends circumferentially transversely substantially at or slightly above the waist line of the wearer, and a similar insert 8 is arranged between the section 6 and a section 9, which latter section is located above the section 6. A pair of similar inserts 10 are arranged between the margins of sections which constitute the portion 9 of the front of the garment and extend from the upper edge of the insert 8 to the upper edge of the front of the garment. A substantially U-shaped insert is applied within a cut formed in the upper portion of each side section 2 and is preferably of the same material as the inserts previously described, and, as shown in Figure 2, another insert 12, corresponding to the inserts 11 and of the same material, is arranged in the upper portion of the back section 3.

It will be observed by reference to Figure 1 of the drawing that the inserts 5 and 8 are slightly curved, the insert 5 being curved upwardly toward its ends and the insert 8 curved downwardly toward its ends, and due to the fact that these inserts are made of material which is capable of being ventilated, and, because of the peculiar arrangement of the inserts 5 and 8, the stomach of the wearer will be restrained from protruding as occurs, however, in the use of corselets as heretofore constructed.

Preferably an insert of rubber or other elastic material indicated by the numeral 13 is arranged in each side member 2 of the corselet and thus not only facilitates putting on the corselet and removing it but also renders the same more comfortable and particularly when the wearer is seated.

What I claim is:—

1. A corselet embodying upper, lower and intermediate front sections, an insert of net material extending transversely of the front of the garment between and connecting the lower edge of the intermediate section and the upper edge of the lower section, an insert extending transversely of the front of the garment above the first mentioned insert and between and connecting the lower edge of the upper section of the front, and the upper edge of the intermediate section, the lower insert being curved downwardly from end to end.
- 15 2. A corselet embodying upper, lower and intermediate front sections, an insert of net material extending transversely of the front of the garment between and connecting the lower edge of the intermediate section and the upper end of the lower section, an insert extending transversely of the front of the garment above the first mentioned insert and between and connecting the lower edge of the upper section of the front, and the upper edge of the intermediate section, the lower insert being curved downwardly from end to end, and the upper insert being curved upwardly from end to end.
- 30 3. A corselet embodying back and side sections, continuous between their upper and lower ends, upper, lower and intermediate front sections connected with the forward margins of the said side sections, the upper front section and the intermediate section being undivided between their ends, and the lower front section being divided vertically, medially and having means whereby it may be closed, an insert of net material extending between and connecting the lower margin of the upper front section and the upper margin of the intermediate section, an insert extending between and connected to the lower margin of the intermediate section and the upper margin of the lower section, the inserts being connected at their ends to the forward margins of the side sections, and U-shaped inserts of net material in incisions in the back and side sections and extending downwardly from the upper edges thereof.
- 35 40 45 50 In testimony whereof I affix my signature.
LANA MAUD WESSELL.
